UNITED STATES PATENT OFFICE.

WALTER W. BURNHAM, OF BOSTON, MASSACHUSETTS.

CALK FOR RUNNING-SHOES.

SPECIFICATION forming part of Letters Patent No. 402,138, dated April 30, 1889.

Application filed January 25, 1889. Serial No. 297,566. (No model.)

To all whom it may concern:

Be it known that I, WALTER W. BURNHAM, of Boston, in the county of Suffolk, State of Massachusetts, have invented a certain new and useful Improvement in Calks or Creepers for Running-Shoes, of which the following is a description sufficiently full, clear, and exact to enable any person skilled in the art or science to which said invention appertains to make and use the same, reference being had to the accompanying drawings, forming part of this specification, in which—

Figure 1 is a bottom plan view of a shoe-sole provided with a creeping-plate of the ordinary construction; Fig. 2, a sectional view of the same; Fig. 3, a bottom plan view of shoe-sole provided with my improved calks, and Fig. 4 a side elevation of one of the calks detached.

Like letters of reference indicate corresponding parts in the different figures of the drawings.

My invention relates to that class of calks which are employed by runners, base-ball players, and others employed in similar athletic pursuits, to prevent their shoes from slipping on the ground; and it consists in certain novel features, as hereinafter fully set forth and claimed, the object being to produce a simpler, cheaper, and more effective article of this character than is now in ordinary use.

The nature and operation of the improvement will be readily understood by all conversant with such matters from the following explanation.

In the drawings, A represents the shoe-sole, and B a creeping-plate of the ordinary form and construction. The plate B consists of a thin triangular metallic sheet open at x in its central portion, and having its corners or ends bent at as nearly right angles as possible to the body thereof to form calks b, the plates being secured to the sole of the shoe by screws or rivets d. To obtain the requisite lightness, the plate B is ordinarily constructed of very thin steel, and in bending the points to form the calks these parts are greatly weakened, rendering them liable to be easily broken from

the body. Moreover, as there is no bearing-surface for the foot of the wearer outside the calks, when the shoe becomes wet the pressure of the calks, especially the one at the toe portion, forces the adjacent portion of the plate-body into the sole, as shown in Fig. 2. 55 This causes said calk to gradually flatten, and by the leverage thus obtained to force the screws d out from the shoe, thereby loosening the plate and frequently breaking them between the calks. The calks b being integral 60 with the plate, it is impossible to so adjust said plate on the shoe that the bearing-points will be disposed in the proper places to suit the wearer. My invention obviates these and other objections, and in carrying it out I construct the calk D with a circular bed-plate, f, (see Fig. 3,) the blade m projecting centrally therefrom and at right angles.

The blade m extends laterally across the face of the plate f, and is formed integral 70 therewith, being rolled from finely-tempered steel. A screw-hole is formed in the bed-plate f at each side of the blade, through which screws or rivets i are inserted in attaching the calk to the shoe.

It will be seen that in my improvement an equal bearing for the foot is supplied at each side of the blade, rendering the calks far less liable to become loosened and preventing them from easily indenting the shoe-sole, 80 whereby they may be worn with much less inconvenience than when of ordinary construction.

The calks thus formed may also be easily adjusted on the sole in positions to suit the 85 "tread" of the wearer.

Having thus explained my invention, what I claim is—

The calk D, comprising the bed-plate f, provided with holes i, and the blade m, formed 90 centrally and integral therewith and projecting at right angles therefrom, substantially as described.

WALTER W. BURNHAM.
